UNITED STATES PATENT OFFICE.

ANNE HARMON, OF IRVINGTON-ON-THE-HUDSON, NEW YORK.

ATHLETIC SKIRT.

1,422,441.

Specification of Letters Patent. Patented July 11, 1922.

Application filed April 10, 1920. Serial No. 372,743.

To all whom it may concern:

Be it known that I, ANNE HARMON, a citizen of the United States, and resident of Irvington-on-the-Hudson, in the county of 5 Westchester and State of New York, have invented certain new and useful Improvements in Athletic Skirts, of which the following is a specification.

This invention relates to improvements 10 in garments for women and children especially designed to be worn when participating in sports, athletic exercises, or the like, and has for its general object to provide a single garment possessing the combined advantages of a skirt and pair of bloomers without the disadvantages of added expense of two separate garments and the encumbering of the wearer's legs by baggy bloomers worn within a skirt.

20 Other objects of the invention are to provide a garment having the graceful appearance of a skirt and so constructed as to permit perfect freedom of motion without exposing the person or undergarments of 25 the wearer; to provide an athletic skirt having a transversely extending diaphragm secured within the same and extending across the skirt in a plane just above the knees of the wearer so as to leave the legs free up 30 to and including the knee joints, and also leave the legs free and unencumbered above the plane of the diaphragm; and to provide an athletic skirt having a transversely extending diaphragm provided with leg openings 35 and so located and constructed that the skirt will fall naturally and evenly from the waist-line when the wearer stands in a normal position, that the wearer may freely move the legs relatively to each other in all 40 directions the maximum extent, and that the diaphragm will not ball up between the knees and crotch and impede the wearer's movements or cause discomfort and chafing.

In the drawings, Fig. 1 is a perspective view, partly in vertical section, of a skirt, illustrating the preferred embodiment of the invention;

Fig. 2 a bottom plan view;

Fig. 3 a fragmentary vertical sectional view, taken on the line III—III of Fig. 2, a part of the diaphragm being shown in front elevation;

Fig. 4 a plan view of the two sections of which the central bridge-piece of the diaphragm is formed;

Fig. 5 a plan view of one of the two end pieces or leg-encircling portions of the diaphragm;

Fig. 6 a plan view showing a slightly modified form of end piece;

Fig. 7 a plan view of the diaphragm without the elastic garters or other means for gathering the full end portions of the diaphragm around the leg openings; and

Fig. 8 a plan view of the diaphragm, without the garters, folded centrally.

Referring to the various parts by numerals, 1 designates a skirt which is preferably of approximately knee-length and provided with a very deep bottom hem 2, the hem being preferably about seven inches deep. A closure or diaphragm 3 is secured within the skirt at a point above the knee line by stitching or otherwise attaching the outer edge of the diaphragm to the inside of the skirt 70 along the hem line, as shown at 4 in Figs. 1 and 3. The diaphragm is provided with leg openings 5 adjacent opposite sides of the skirt, and is elongated in the direction of the width of the skirt for the purposes hereinafter set forth.

The diaphragm is so constructed as to have a general elliptical contour in plan view when attached to the skirt and also to have an excess of material at each end forming 85 full portions around the leg openings, as shown in Figs. 2 and 3. While a diaphragm having the final form shown in the drawings may be made up from varying numbers of pieces of material cut in various shapes, I 90 prefer to form the diaphragm of two end-pieces 6, of similar shape, and two intermediate pieces 7 and 8.

The two pieces of material 7 and 8 are stitched together along their adjacent concave or inwardly curving end edges 9 to form a two part bridge piece having pointed outer end portions or integral gussets formed by the oppositely inclined end edges 10 and 11 of the pieces 7 and 8. The front and rear 100 edges of the pieces 7 and 8 are straight and parallel with each other, as shown in Fig. 4. The end pieces 6 have one long straight side edge and two relatively short straight end edges extending at right angles to said 105 straight side edge. The other side edge of each end piece 6 flares away from the long straight side edge thereof toward each end of the piece so that the end piece gradually increases in width toward its ends. This 110

result may be obtained by cutting this edge of the end piece on a continuous arc, as shown at 12 in Fig. 5, by cutting this edge so as to provide an intermediate straight edge portion 13 and oppositely inclined edge portions 14, as shown in Fig. 6, or in any other suitable manner. The straight side edges of the end pieces 6, or 6^a, are folded upward and stitched to the end piece along 10 the dotted line 15 (Figs. 5 and 6) to form hems 16. The end edges of the pieces 6, or 6^a, from the hem line 15 to the curved or dished side edge thereof, are the same length as the inclined edges 10 and 11 of the outer 15 ends of the two part bridge piece and are stitched thereto as shown in Figs. 7 and 8, thus forming full portions of peculiar form at the ends of the diaphragm having leg openings 5 therethrough bounded by the 20 hemmed edges 16 of the end pieces.

The ends of each of the hems 16 meet at the apex of the adjacent pointed or gusset portion of the central bridge. These hems form very large openings and the full portions 25 of the diaphragm around the leg openings are gathered by confining in each hem 16 an elastic band or garter 17 of suitable size to securely grip the wearer's leg above the knee. It will be obvious that draw- 30 strings, tapes, or the like may be employed instead of elastic garters, if desired.

The total length of the front and rear edges of the central bridge piece and the dished edges of the two end pieces, which 35 form the outer edge of the completed dia- phragm, equals the length of the stitched upper edge of the hem 2 of the skirt, or the circumference of the skirt at the point of connection of the diaphragm therewith. The 40 straight front and rear edges of the pieces 7 and 8 are stitched to the front and back of the skirt, respectively, along the upper edge of the hem 2, and the dished edges of the end pieces 6 are stitched along the re- 45 maining portions of the hem line at op- posite sides of the skirt.

By constructing the diaphragm as above described, the skirt will not be pulled inwardly fore and aft at the inner side of each 50 leg opening when the adjacent portions of the diaphragm are gathered around the leg openings, as shown in Figs. 2 and 3. It will also be observed that the elongated dia- phragm, provided with full leg-encircling 55 portions formed by the end pieces 6 and pointed gusset portions of the central bridge, permits free maximum movement of the legs in all directions relatively to each other, and will not drop below the bottom of the 60 skirt at any point. The diaphragm extends across the skirt between the knees and the tops of the wearer's stockings and is so constructed that it will not become bunched between the legs above the stockings or sag 65 downwardly so as to be visible below the

skirt, and will not draw the skirt inward between the wearer's legs. By forming the bridge piece of two members 7 and 8 having dished edges 9 stitched together, unnecessary fullness of the diaphragm between the legs 70 is avoided and the width of the diaphragm centrally from front to rear is increased, permitting natural sagging of the dia- phragm in the center without distorting the skirt. 75

In use the garters 17 are preferably pushed up about the legs to a point about midway the upper and lower edge of the hem 2, as shown in Fig. 1, in which position the full- ness at the ends of the diaphragm around 80 the leg openings 5 permits considerable free- dom of movement of the legs in all direc- tions without pulling on the line 4 and dis- turbing the natural hang of the skirt. The skirt 1 may be accordion plaited, as shown, 85 or may be plain. It will be obvious that a full skirt, if accordion plaited, will normally hang more closely about the wearer's body than a plain full skirt.

It will be observed in Fig. 4 (which is a 90 plan view of the bloomer section extended) that the outside or lower edges of the leg- openings project in this position a consider- able distance beyond the upper edges there- of which are secured to the skirt. This en- ables the wearer to spread her legs a great 95 distance beyond the limits of the seam line 4; consequently, any wide stride of the wearer will not draw or affect the hang of the skirt. This extra length of the bottom of the bloom- 100 ers is secured by forming the central panel wider across its center than at its edges and shaping the blanks of the leg-sections with one cut-out side, as at 12, so that when the leg-sections are secured to the central panel 105 the narrowest portions of said leg-sections are located at the outside, and, as the top edge of the diaphragm, including the leg- 110 portions, is secured to the skirt on a hor- 115 izontal line, this inclines the bottom edges of the leg-portions upwardly and outwardly and consequently causes the outer lower por- 120 tion of the leg sections to project beyond the secured edge at the top side. In other words, the length of the bottom of the diaphragm 125 taken on a center line, which is the limit of spread, is greater than the length of the space between the extremities of the top edge where it is secured to the skirt.

It will be observed further that the length 120 of the central panel from one leg-opening to the other is greater than the width of the same from the front to the back of the skirt, so that, when the diaphragm including the leg-portions is expanded, it will be approxi- 125 mately oval in shape, which will permit a greater stretch in one direction than in the other.

The arch formed by the seam uniting the curved edges of the pieces 7 and 8 curves out- 130

wardly and upwardly from the center to the front and rear sides of the skirt, and the seam formed at 10 and 11 extends upwardly and inwardly from the leg-openings to the 5 front and rear sides of the skirt, so that the leg-openings and the central panel, except at its front and rear edges, are thereby positioned to lie in a plane below the contour seam-line 4. This manner of connecting the 10 section forms the depending leg-portions having depending outer sides which are shorter in length from the seam-line 4 to the leg-opening than is the center dimension of either of the sections 7 or 8 from the leg- 15 opening to the seam-line 9. Thus, extending between the leg-openings is the long panel section, which in normal positions is prevented from sagging below the plane of the leg-openings preferably by the arched seam 20 9 and also forms long inside leg-portions, and at the outside of each leg-opening is the relatively short leg-portion which prevents sagging of the outside of the leg-portions and permits a freedom of outward movement 25 beyond the limits of the seam-line 4 at both sides of the garment simultaneously.

What I claim is:

1. A skirt having a flexible diaphragm embodying depending leg-portions each being 30 constructed from a piece of material having one straight long-side, end-edges formed at right-angles to said straight long-side, an opposite long-side which flares away from 35 said straight long-side toward its ends to

form a short outer side for the depending 35 leg-portion, and an extended central panel to form long inner sides for both leg-portions and to the side-edges of which are connected the straight end-edges of the leg- 40 portions, the flaring edges of said leg-portions and the front and rear edges of said central panel being secured all around the inner side of the skirt between the bottom edge and the waist-line thereof.

2. A skirt having a flexible diaphragm 45 embodying depending leg-portions each being constructed from a piece of material having one straight long-side, end-edges formed at right-angles to said straight long-side, an opposite long-side which flares away 50 from said straight long-side toward its ends to form a short outer side for the depending leg-portions, and an extended central panel to form long inner-sides for both leg-portions and to the side-edges of which are connected the straight end-edges of the leg-portions 55 and provided with a central downwardly-arched seam extending between the front and rear sides of the skirt to support the central portion above the bottom edges 60 of the leg-portions, the flaring edges of said leg-portions and the front and rear edges of the central panel being secured all around the inner-side of the skirt between the bottom-edge and the waist-line thereof. 65

In testimony whereof I hereunto affix my signature.

ANNE HARMON.
